UNITED STATES PATENT OFFICE.

JOHN C. HUB, OF CLEVELAND, OHIO.

INDEX-CARD.

1,150,034.

Specification of Letters Patent. Patented Aug. 17, 1915.

Application filed November 27, 1914. Serial No. 874,292.

To all whom it may concern:

Be it known that I, JOHN C. HUB, a citizen of the United States, residing at Cleveland, in the county of Cuyahoga and State 5 of Ohio, have invented certain new and useful Improvements in Index-Cards, of which the following is a specification.

This invention relates generally to card indexes, and particularly to index cards 10 having insertible tab structures.

More specifically the invention relates to an index card having a tab portion provided with a recess extending from one lateral edge to a point near the opposite edge, 15 together with a casing of transparent material such as celluloid enveloping the tab and forming with the recess therein a pocket for the reception of an insert.

The invention may be further briefly summarized as consisting in the construction and combination of parts hereinafter set forth in the following description, drawings and claims.

Referring to the drawings, Figure 1 is a 25 view showing the face of a card provided with a tab recess before the casing is applied thereto and before the tab is trimmed; Fig. 2 shows the card with the casing applied for trimming; Fig. 3 is a similar view 30 after the tab structure is trimmed; Fig. 4 is a section upon the line 4-4 of Fig. 3; Fig. 5 is a section upon the line 5-5 of Fig. 3; Fig. 6 is a modified form wherein the tab casing is made up of a folded piece of celluloid with an inner strip of celluloid adjacent to the folded edge forming a homogeneous celluloid upper edge structure for the tab; Fig. 7 is a section upon the line 7-7 of Fig. 6; and Fig. 8 is a section upon 40 the line 8-8 of Fig. 6.

In carrying out the invention any preferred form and style of card and tab structure may be employed so long as they possess the necessary characteristics, but I have 45 shown one arrangement and in such embodiment 1 represents a card, which, in the early steps of the formation of the finished prod-

uct, is provided with a longitudinally disposed rectangular recess 2 arranged near its upper edge. Engaging over this upper 50 edge and covering this recess is an envelop of celluloid formed from a single piece bent over the edge and comprising a front plate portion 3 and a rear plate portion 4, the latter being provided with an opening 5 55 through which a pin or other device may be inserted for moving the insert strip 6. After the casing 3 is applied to the card, then the upper edge of the card including the envelop are trimmed to form a tab structure and the cut is arranged so that it cuts the end of the recess 2, so as to make an open-ended pocket in the tab structure for the reception of the insert 6 containing any desired legend. 65

In the modification shown in Figs. 6, 7 and 8, the card is provided with a recess 7, shown in dotted lines in Fig. 6, extending inward from the upper edge, and the casing comprises the folded strip of celluloid forming the front plate 8 and the rear plate 9 similar in all respects to the other casing except that above the recess and within this casing is a strip of celluloid 10 amalgamated with the casing and forming a homogeneous 75 celluloid edge structure. In this form, the rear plate 9 is provided with an opening 11 furnishing a means for manipulating the insert strip. 70

Having described my invention, I 80 claim:—

1. A tabbed sheet comprising a sheet, a tab integral therewith and having an open-ended recess extending inward from one end of the tab, the upper and lower edges 85 of the tab at the recess forming parallel edge guides for an insert, and side plate portions of transparent celluloid extending over both sides of the tab, the recess and the adjacent portions of the sheet and forming with the recess in the tab an open-ended pocket for an insert. 90

2. An index sheet structure comprising a sheet having an integral tab extending be-

yond the tab edge thereof and provided with a recess extending inward from one end of the tab and closed within the tab by a portion thereof, the edges of the tab at the recess being straight and parallel, and a celluloid binder folded over the sides of the tab, the recess and the adjacent portions of the sheet and forming with the recess in the tab an open-ended insert pocket

having parallel edge guides for a designat- 10
ing insert.

In testimony whereof I affix my signature in presence of two witnesses as follows:

JOHN C. HUB.

Witnesses:

G. O. FARQUHARSON,
C. H. SHOTZBARGER.
